United States Patent Office

Des. 185,290
Patented May 26, 1959

185,290

JEWELRY PENDANT OR THE LIKE

Joseph Kovacs, Bronx County, N.Y.

Application March 4, 1958, Serial No. 49,891

Term of patent 14 years

(Cl. D45—17)

FIG.1

FIG.5

Fig. 1 is a front elevational view of a jewelry pendant or the like, showing my new design;

Fig. 2 is a rear elevational view;

Fig. 3 is a side elevational view;

Fig. 4 is a sectional view taken on the line 4—4 of Fig. 1; and

Fig. 5 is a sectional view taken on the line 5—5 of Fig. 2.

I claim:

The ornamental design for a jewelry pendant or the like, substantially as shown.
